DESIGN FOR A BICYCLE FENDER FLAP

Walter C. Jackson, Rahway, N. J.

Application December 18, 1935, Serial No. 60,159

Term of patent 7 years

To all whom it may concern:

Be it known that I, Walter C. Jackson, a citizen of the United States, residing at Rahway, in the county of Union and State of New Jersey, have invented a new, original, and ornamental Design for a Bicycle Fender Flap, of which the following is a specification, reference being had to the accompanying drawing, forming part thereof, in which:

Figure 1 is a face view of the bicycle fender

flap, showing my new design, and Figure 2 is a cross section taken at about the plane of the line 2—2 of Figure 1.

I claim:

The ornamental design for a bicycle fender flap, as shown.

Signed at Rahway, New Jersey, this 6th day of December, 1935.

WALTER C. JACKSON.
